(57) **CLAIM**

The ornamental design for a slit armrest, as shown and described.

DESCRIPTION

FIG. 1 is a front, right, and top perspective view of a slit armrest, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front, right, and top perspective view of the slit armrest of FIG. 1, shown with the storage box in an alternate open position of use.

The broken lines shown in the drawings are included for the purpose of illustrating portions of the slit armrest that form no part of the claimed design.

1 Claim, 9 Drawing Sheets
